United States Patent Office

Des. 178,364
Patented July 31, 1956

178,364

SLIDE PROJECTOR

Frederick W. Hertzler, Detroit, Mich., assignor to Argus
Cameras, Inc., Ann Arbor, Mich., a corporation of
Michigan

Application December 2, 1953, Serial No. 27,869

Term of patent 14 years

(Cl. D61—1)

Fig. 1

Fig. 2

Figure 1 is a side elevation view of a slide projector showing my new design, the opposite side not shown is the same as that shown;

Figure 2 is a top plan view of the slide projector;

Figure 3 is a front elevation view of the slide projector; and

Figure 4 is a rear elevation view of the slide projector. I claim:

The ornamental design for a slide projector, as shown and described.
